23 26 Daniel H. Davis
by Bair & Freeman Attorneys

UNITED STATES PATENT OFFICE.

DANIEL H. DAVIS, OF MARSHALLTOWN, IOWA, ASSIGNOR TO PETER N. ANDERSON,
OF MARSHALLTOWN, IOWA.

GATE.

Application filed September 10, 1925. Serial No. 55,520.

The object of my invention is to provide a gate of simple, durable and comparatively inexpensive construction, having a remote control.

A further object is to provide a gate which can be easily opened or closed by pulling a control cord, which may be located wherever convenient.

Still a further object is to provide such a gate having a hollow gate post at the hinged end in which the operating mechanism is enclosed.

Still a further object is to provide novel means whereby the gate is automatically unlatched when the control cord is pulled for opening the gate.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a plan view of my gate illustrating it in closed position.

Figure 2 is a side elevation of the same.

Figure 3 is a sectional view on the line 3—3 of Figure 2.

Figure 4 is a sectional view on the line 4—4 of Figure 3; and

Figures 5 and 6 are views of the mechanism within the hollow gate post showing them in different positions, which they assume during operation.

On the accompanying drawings, I have used the reference numeral 10 to indicate a fence, which is of any construction desirable. Two gate posts 11 and 12 are provided, and they are preferably set in concrete to maintain their alignment.

Hinge members 13 are secured to the gate post 11.

A gate 14 has hinge members 15 secured thereto.

A hinge pin 16 extending through the members 13 and 15 permits the gate 14 to swing about the post 11.

On the gate post 12, a stop rail 17 is provided for the gate 14 to swing against when the gate is closed. For retaining the gate 14 in closed position, a catch member 18 is secured to the post 12.

A second latch member 19 is slidably mounted in the end member 20 of the gate

14, and is positioned to coact with the catch 18 when the gate is closed.

A leaf spring 21 holds the latch 19 in position to engage the catch 18, and as clearly shown in Figure 1, the latch 19 will be 60 pushed back against the action of the spring 21 by the cam surface 22 of the catch 18.

Before opening the gate, it is necessary to unlatch the latch 19 and the mechanism for accomplishing this result, will be later described.

A hollow box-like post 23 is composed of sides 24 and ends 25, and is secured to the gate post 11. Three sets of guide grooves 26 are formed in sides 24 of the post 23. 70

A weight member 27 is slidably mounted in the center groove 26, and engaging members 28 and 29 are slidably mounted in the outside grooves 26.

Loosely mounted on the top of the hinge 75 pin 16 is a pulley 30. A cable or rope 31 is attached at its center to the pulley 30 by a screw or clamp 32.

The ends of the cable 31 extend through openings 33 in one of the sides 24 of the 80 post 23 and thence over pulleys 34, and down to the engaging members 28 and 29 to which they are secured. Two stop members 36 and 37 are formed on the pulley 30 in position to engage opposite sides of the gate 85 14 and to allow slight rotation of the pulley 30 relative to the gate 14. The pulleys 34 are supported by a partition 35 in the post 23.

Hinged at 38 to each of the engaging members 28 and 29 is a plate 39 having at its center an extending portion 40. At the edges of the plate 39 are extensions 43 which are bent as clearly shown in the lower part of Figure 3. 90

The extensions 43 extend through openings 44 in the engaging members 29.

A light leaf spring 42 bearing against the extension 40 normally holds the plate 39 in the position shown in the lower part of Figure 3. The extensions 43 limit the position of the plate 39 as it is forced outward by the spring 42. 100

On each end 25 of the box 23, stronger leaf springs 41 are mounted in the path of 105 the extensions 40.

It will be seen that when the engaging member 29 or 28 is raised so that the extension 40 strikes the spring 41, the spring 41 will cause the plate 40 to assume the 110

position illustrated in the upper part of Figure 3, against the action of the weaker spring 42. The weight member 27 is provided with ears 45 which are designed to coact with the extensions 43 when said extensions are held away from the members 28 and 29 by reason of the springs 42.

Additional weights 46 in the quantity necessary to operate my gate, are hung by chains 47 on the weight member 27.

A control cord or rope 48 is secured to the weight member 27, and extends upward through a hole 49 in the partition 35 and through a hole 50 in the top 51 of the post 15 23.

The rope 48 extends to any point convenient for operating the gate from, or a plurality of control cords 48 may extend to a plurality of remote control points so that 20 when any one of said cords are pulled, the gate is caused to operate.

An ear 52 is secured to the pulley 30 to which a short cable 53 is attached. The cable 53 extends around a pulley 54, and has 25 its other end attached to a lever 55, which is pivoted to the gate 14 at 60.

A rod 56 extends through an opening 59 in the latch 19, and terminates in a head 58.

From the foregoing, it will be seen that 30 when the pulley 30 is moved clockwise in Figure 1, the stop 37 will leave the gate 14 and the stop 36 will engage the gate. This slight movement will pull the cable 53, swing the lever 55 and cause the rod 56 to slide to 35 the left in Figure 2.

The head 58 engaging the latch 19 will cause it to slide against the action of the spring 21, thereby unlatching the gate to 40 allow it to be opened. It is obvious, referring to Figure 2, that the latch 19 is free to move to the left without affecting the rod 56, which it does when the latch is pushed back by the cam surface 22 of the catch 18 when the gate 14 is nearly closed.

In the operation of my gate, the cord 48 is 45 pulled, raising the weight member 27 and the weight 46.

As the member 27 nears the upper limit of its movement, the ears 45 engage the extensions 43, and force them against the engaging member (28 or 29 as the case may be) against the action of the spring 41, as clearly shown in Figure 5.

Further movement of the member 27 50 causes the ear 45 to pass the extensions 43, thereby allowing the spring 41 to cause the plate 40 to again assume the position shown in the upper part of Figure 3.

Upon releasing the control cord 48, the 60 member 27 starts to descend due to its weight and that of the weights 46. The ears 45 then engage the extensions 43, and thereby cause the engaging member 28 to also descend. This pulls the cable 31 secured to 65 the member 28 and rotates the pulley 30.

This causes the gate to be unlatched as above described, and then the stop 36 engages the gate and swings it to the open position, shown in dotted lines in Figure 1.

The post 61 has a bumper 62 made of rubber or other suitable material to cushion the gate in open position. Before the gate 14 is fully opened, the weights 46 rest on the ground as illustrated in Figure 6, the chain 47 being slack.

This automatically relieves the cable 48 of the weights 46 so that the gate 14 is not slammed so violently against the stops 62 or 75 17 at the end of its travel when opening or shutting.

The weight member 27 is sufficient to continue the opening or shutting of the gate 14 after the weights 46 rest on the ground and also to firmly hold the gate in open position against the bumper 62 or to latch the gate 85 when closing it.

When the control cord 48 is again pulled for raising the weight member 27, the ears 45 are disengaged from the extensions 43, and a similar engaging action takes place 90 between the weight member 27 and the engaging member 29. This action rotates the pulley 30 counter-clock wise in Figure 1, the stop 37 engages the gate 14, and it is then 95 closed.

It is obvious that movement downward of the engaging member 28 raises the member 29 to position to be engaged by the weight member 27 and vice versa.

For access to the parts of my device for 100 oiling or adjusting the weights 46 etc., I provide a door 63, which may be hinged at 64 and latched at 65.

It is also obvious that the weight member 27 holds the gate 14 open and therefore no 105 latch is necessary to keep it open.

From the description here given, it will be seen that I have provided a gate which accomplishes the objects contemplated and does so with a minimum of parts.

In operation, I have found that ten pounds weight is sufficient to quickly open an ordinary size gate, and it is therefore seen that but little energy is required to 110 operate a gate of this type.

Some changes may be made in the construction and arrangement of the various parts of my invention, and it is my intention to cover by my claims, any modified forms of structure or use of mechanical 115 equivalents, which may be reasonably included within their scope.

I claim as my invention:

1. A gate of the class described, comprising a hollow gate post, a gate swingably mounted thereon, a pulley on said gate, a cable secured to said pulley and having its ends extending into said post, a weight 120 slidably mounted in said post, a control cord for raising said weight and means for auto- 125 130

imatically causing alternate engagement between said weight and the ends of said cable.

2. A gate of the class described, comprising a gate post, a gate swingably mounted thereon, a pair of engaging members and a weight member mounted for vertical sliding movement in said post, a control cord for raising said weight member, a pulley mounted on said gate, cables extending from said engaging members to said pulley and means for disengagement between one of said engaging members and said weight member, and engagement between the other engaging member, and said weight member, when said control cord is pulled whereby said weight will cause said pulley to rotate for opening or closing said gate.

3. A gate of the class described, comprising a gate post, a gate swingably mounted thereon, a pair of engaging members and

a weight member mounted for vertical sliding movement in said post, a control cord for raising said weight member, a pulley rotatively mounted on said gate stops on said pulley for engaging said gate for allowing only slight rotating movement of said pulley relative to said gate, cables extending from said engaging members to said pulley and means for disengagement between one of said engaging members and said weight member, and engagement between the other engaging member and said weight member, when said control cord is pulled whereby said weight will cause said pulley to rotate for opening or closing said gate, a latch on said gate, and means connecting said latch to said pulley whereby when said pulley is slightly rotated before opening said gate, said latch is unlatched.

DANIEL H. DAVIS.
